UNITED STATES PATENT OFFICE.

PETER R. PETERSON, OF SALT LAKE CITY, UTAH, ASSIGNOR TO PETERSON-HARNDON CLUTCH COMPANY, OF SALT LAKE CITY, UTAH, A CORPORATION.

FLUID-CLUTCH.

1,307,697.

Specification of Letters Patent. Patented June 24, 1919.

Application filed March 26, 1918, Serial No. 224,899. Renewed April 2, 1919. Serial No. 287,073.

To all whom it may concern:

Be it known that I, PETER R. PETERSON, a citizen of the United States, residing at Salt Lake City, in the county of Salt Lake 5 and State of Utah, have invented certain new and useful Improvements in Fluid-Clutches, of which the following is a specification.

My invention relates to clutch mechanism 10 and has for its object to provide a fluid clutch which is economical and efficient and by which power may be gradually transmitted from a driving to a driven shaft within a small space, and by new and novel means.

These objects I accomplish with the machine illustrated in the accompanying drawings in which similar letters and numerals of reference indicate like parts throughout the several figures and as described in the 20 specification forming a part of this application and pointed out in the appended claim.

In the drawings in which I have shown a substantial embodiment of my invention, Figure 1 is a longitudinal diametrical section of the machine. Fig. 2 is a cross section on line 2—2 of Fig. 1. Fig. 3 is a view in perspective of the sliding vane.

The present invention consists of a cylindrical cup shaped casing A integral with 30 the driven shaft B. A sleeve C having an extended flange D thereon is bolted on said casing A as a partial closure therefor by the bolts 1.

An inwardly extending lug 2 is detachably 35 secured to the inner wall of said casing A by the tap bolts 3, which lug has one face curved to conform to the face of the inner wall of said casing A to form a fluid tight joint therebetween. The other face of said 40 lug 2 is gradually inclined toward the inner wall of said casing A to form an edge, as shown at 4, and more sharply inclined at its other edge, as shown at 5, the purpose of thus forming said inwardly extended lug 45 2 with inclined faces will be more fully explained hereinafter. Annular packing channels 6 and 7 are cut in the wall of said flange D and sleeve C respectively within which are carried packing bands 8 and 9.

50 An annular rotor E is secured on the end of the driving shaft and is journaled in said sleeve C and concentrically operated within said casing A.

The peripheral face of said rotor E con- 55 tacts with the inner wall of said lug 2 and

forms an annular liquid channel F between the outer face or periphery of said rotor and the wall of said casing A, of even depth except where said lug 2 extends therein. A compound slide valve G is diametrically 60 mounted in and carried by said rotor E. The said valve G consists of a round casing 10 within which is carried the spiral spring 11. One portion of the said valve G consists of a rectangular vane member 12 with its 65 end portion adapted to close the said annular liquid channel F when held therein by said spring 11, one end of which bears against one end of said member. In the outer end portion of said vane member 12 70 is provided an opening 13, and within said member 12 is slidably operated a slide valve 14 to open and close said opening 13. Another spiral spring 15 is carried by a plate 17 in said member 12 behind said slide valve 75 14 to normally hold the valve over said opening 13.

A slotted opening 16 is cut in the side edge of said vane member 12 and a smaller opening is cut adjacent thereto in the said valve 80 14. A detent 18 which is pivoted on the end of a lever 19 is made to engage within the slot in said valve 14 and by which said valve is operated. A lever 19 to operate said valve 14 and said vane member 12 is pivoted to 85 the driving shaft H.

A channel 20 is cut longitudinally and radially in the side of said driving shaft H within which one end of said lever 19 is pivoted and the other end of said slot is 90 broadened to allow free action of the end of said lever when moving said compound valve G. A sleeve collar 22 is carried on said shaft H and a lug 23 is detachably secured on the inner wall of said collar 22 by 95 the tap bolts 24. The said lug 23 is operable in said slot 20. An annular channel 25 is cut in said collar sleeve 22 and one end of a lever, not shown, is to engage in said channel by which said sleeve collar 22 is moved longitudinally on said shaft H. 100

The operation of my machine is as follows:

With fluid such as oil introduced into said channel F through the conduit 26, to fill 105 said channel, power applied to the driving shaft H will be transmitted to the driven shaft B as the rotation of said rotor E is impeded by said oil. With all of the elements in position as shown in full lines in 110

the drawings full power will be transmitted from the driving to the driven shaft. To throw out the clutch the said collar sleeve 22 is moved longitudinally on said shaft H toward the rotor E, this will move the lever 19 on its pivot and the end of the lever 19 engaging the end of the slot 16 in the vane 12, will withdraw said vane radially from the channel F to the position shown in dotted lines in Fig. 2, and the said springs 15 and 11 will be compressed sufficiently to allow the vane 12 to be withdrawn from said channel, and no power will be transmitted. When slow speed is desired in the driven shaft B, the collar sleeve 22 is moved on said shaft H, away from the rotor, and the lug 23 will release the lever 19. The spring 11 will move vane 12 radially outward and partially close the channel F, to increase the speed of the driven shaft gradually continue the movement of the collar 22 away from the rotor E. This may be done until the end of vane 12 contacts with the inner peripheral wall of said casing A, and closes the said channel F except that oil may flow through the opening 13, and the speed of the driven shaft will be about what is usually termed low speed. To increase the speed beyond what is termed low speed the collar 22 is to be moved farther away from said motor. This will continue to release the lever 19 and the compression of spring 15 will then be gradually released and the valve 14 will gradually close the opening 13, and as said collar 22 is then

moved back and forth on said shaft H the speed may be gradually increased or decreased as desired.

The centrifugal force applied to the oil and the packing 8 and 9 will prevent any leakage of the oil from said channel F when the machinery is in operation and at other times only sufficient oil will leak from said channel to lubricate the parts. Any wear on the lugs 2 and 23 may be corrected by removing said lugs and supplying new ones.

I thus provide a compact efficient clutch adjustable as to the amount of power transmitted by the flow of fluid in a channel; a novel compound valve and means to move said valve to regulate the flow of fluid in said channel.

Having thus described my invention and the operation thereof I desire to secure by Letters Patent and claim:—

In a fluid clutch the combination of a casing connected with a driven shaft; a radially slotted rotor spaced from and concentrically operated within said casing; and connected with a driving shaft; a vane operable in the slot in said rotor to close the space between said rotor and its casing as desired, and having an opening in said vane; a slide valve to close the opening in said vane; and means to move said valve on said vane in said rotor.

In testimony whereof I have affixed my signature.

PETER R. PETERSON.
